Primary Examiner—Elizabeth A Albert(74) *Attorney, Agent, or Firm*—Christensen O'Connor Johnson Kindness, PLLC(57) **CLAIM**

The ornamental design for a pen, as shown and described.

DESCRIPTION

FIG. 1 is a lower front left perspective view of a pen showing my new design;

FIG. 2 is a left side elevation view thereof;

FIG. 3 is an enlarged top plan view thereof;

FIG. 4 is a front elevation view thereof;

FIG. 5 is a right side elevation view thereof;

FIG. 6 is an enlarged bottom plan view thereof; and,

FIG. 7 is a rear elevation view thereof.

The broken line showing the top surface in FIG. 3 is included for the purpose of illustrating environment and forms no part of the claimed design.
